CLAIM

The ornamental design for a gas alarm, as shown and described.

DESCRIPTION

FIG. 1 is a front perspective view of a first embodiment of a gas alarm showing my new design;

FIG. 2 is a rear perspective view of the first embodiment of the gas alarm;

FIG. 3 is a front view of the first embodiment of the gas alarm;

FIG. 4 is a rear view of the first embodiment of the gas alarm;

FIG. 5 is a right side view of the first embodiment of the gas alarm;

FIG. 6 is a left side view of the first embodiment of the gas alarm;

FIG. 7 is a top view of the first embodiment of the gas alarm;

FIG. 8 is a bottom view of the first embodiment of the gas alarm;

FIG. 9 is a front perspective view of a second embodiment of the gas alarm;

FIG. 10 is a rear perspective view of the second embodiment of the gas alarm;

FIG. 11 is a front view of the second embodiment of the gas alarm;

FIG. 12 is a rear view of the second embodiment of the gas alarm;

FIG. 13 is a right side view of the second embodiment of the gas alarm;

FIG. 14 is a left side view of the second embodiment of the gas alarm;

FIG. 15 is a top view of the second embodiment of the gas alarm; and,

FIG. 16 is a bottom view of the second embodiment of the gas alarm.

(Continued)

The broken lines showing in the figures are included for the purpose of illustrating portions of the gas alarm that form no part of the claimed design.
